UNITED STATES PATENT OFFICE.

DANFORTH H. ROYCE, OF COLUMBUS, OHIO.

FLY-FAN, &c.

SPECIFICATION forming part of Letters Patent No. 268,730, dated December 5, 1882.

Application filed October 23, 1882. (No model.)

To all whom it may concern:

Be it known that I, DANFORTH H. ROYCE, of Columbus, in the county of Franklin and State of Ohio, have invented certain new and useful Improvements in Fly Fans or Brushes and Ventilators; and I do hereby declare the following to be a full, clear, and exact description of the invention, such as will enable others skilled in the art to which it pertains to make and use it, reference being had to the accompanying drawings, which form part of this specification.

My invention relates to an improvement in ventilators and fly fans or brushes; and it consists, first, in the combination of a suitable driving mechanism, a shaft provided with a friction-wheel which is adjustable back and forth thereon, and a vertical shaft having a friction-wheel on its lower end and adjustable arms or blades upon its upper end, whereby the vertical shaft can be made to revolve at any desired rate of speed.

It still further consists in the combination, with the vertical shaft, of a supporting-plate provided with a spring locking device, and a suitable toothed plate which is placed upon the top of the supporting-plate, and the revolving arms which are provided with a toothed segment to engage with the toothed plate, whereby each one of the arms can be adjusted to the same angle at the same time.

The object of my invention is to provide a ventilator fly brush or fan which is especially adapted for restaurants, lunch-counters, and tables, and in which the arms can all be given the same inclination, so that it will create a draft of air in any desired direction.

Figure 1 is a side elevation of my invention. Fig. 2 is a detail view of the same.

A represents an inclosing box or frame, which may be placed upon a lunch counter or table, and in which the spring-actuated driving mechanism B is placed. If preferred, this driving mechanism may be placed underneath the counter, and then have the driving-shaft passed up through it, in which case the driving mechanism may be secured to the under side of the counter, or to any other suitable support, and the box or frame dispensed with. By using a box or frame, however, the fan is made portable, and can be used wherever it may be desired. Extending from this driving

mechanism B is the shaft C, upon which is placed a rubber-faced friction-wheel, D. This wheel can be adjusted back and forth upon the shaft by means of a lever, E, for the purpose of increasing or decreasing the speed at which the revolving arms or fans are run, as may be desired.

Screwed through the top of the box or frame A, or the counter or table, is the lower end of the standard F, which receives the clamping-nut G on its lower end for the purpose of holding the standard rigidly in place. Passed up through this standard is the driving-shaft H, upon the lower end of which is placed the friction-wheel I. This vertical shaft has a slight vertical play, so that the friction-wheel upon its lower end can be raised up out of contact with the driving friction-wheel, and so that the driving friction-wheel can be adjusted back and forth under it for the purpose of increasing or decreasing the speed at which the arms are being driven. As the whole weight of the vertical shaft and the driving-arms will rest directly upon the driving friction-wheel, sufficient frictional contact is always insured to drive the vertical shaft.

Secured to the vertical driving-shaft above the top of the standard is a supporting-plate, J, through which passes a spring locking device, L, of any suitable description. Upon the top of this supporting-plate is placed the adjusting plate or wheel N, which has beveled teeth upon its outer edge, and with which the toothed sections O upon the arms or fans P engage.

Upon the top of the toothed plate or wheel is placed a suitable casting, R, which has a number of sockets proportioned to the number of arms or fans which are to be used, and which casting is secured to the driving-shaft in any suitable manner. Each one of the arms or fans has its inner end swiveled in its socket, so that it can turn partially around for the purpose of being adjusted to any desired angle. As each one of the arms or fans has a segment which meshes with the plate or wheel, it is only necessary to loosen the spring-catch, and then turn the wheel or plate, when each one of the arms or fans will be adjusted at the same time to the same angle. By means of this adjustment the fans can be turned so as to produce a current of air in any direction.

while revolving. Secured to the standard at a suitable distance below the fans are the arms S, of which there may be any desired number, and upon which bananas and other such fruit 5 may be hung. Below these arms may be placed a suitable basket, T, for holding fruit, cakes, nuts, or any other things of a similar nature. Upon the lower end of the standard will extend from each side an arm which will serve 10 as a support for a caster.

It is only necessary to wind up the spring-motor, and then adjust the lever which shifts the driving friction-wheel to any one of the notches in the hanging frame U, when the 15 arms or fans will continue to revolve at a desired rate of speed until the spring has run down. When the fans are adjusted vertically they produce a very pleasant draft of air, which can be felt for a considerable distance beyond 20 the fan. This fan can also be operated by steam or any other motor that may be preferred.

Having thus described my invention, I claim—

25 1. In a fly-fan and ventilator, the combination of a motor, the shaft C, driven thereby, and provided with the shifting friction-wheel, with the shaft H, having the wheel I on its lower end and a series of fans secured to its

upper one, and the standard F, substantially 30 as shown.

2. In a fly brush or fan, the combination of a series of arms or fans, each one of which is provided with a segment, with an adjusting plate or wheel whereby all of the arms can be 35 adjusted at the same time, substantially as described.

3. The combination, with the revolving shaft having a suitable casting provided with sockets secured to its upper end, of a number of 40 fans or arms which are swiveled in these sockets, and each one provided with a segment, and an adjusting plate, whereby all of the fans or arms can be adjusted at the same time, substantially as set forth.

4. In a fly brush or fan, the combination of the standard through which the vertical operating-shaft passes, and which standard is provided with arms on which fruit and other such things can be hung, and a basket, 50 substantially as specified.

In testimony whereof I affix my signature in presence of two witnesses.

DANFORTH H. ROYCE.
